(57) **CLAIM**

The ornamental design for a crate top, as shown and described.

DESCRIPTION

FIG. 1 is a perspective front view of a crate top;

FIG. 2 is a perspective bottom view of the crate top;

FIG. 3 is a front elevation view of the crate top; the rear elevation view being identical to the front view shown;

FIG. 4 is a left side elevation view of the crate top; the right side view being identical to the left side view shown;

FIG. 5 is a top plan view of the crate top;

FIG. 6 is a bottom plan view of the crate top; and,

FIG. 7 is a cross-sectional view taken on line 7-7 of FIG. 5. The broken lines shown in the drawings that illustrate a crate form no part of the claimed design.
